(57) **CLAIM**

We claim the ornamental design for a precision hoe opener, as shown and described.

DESCRIPTION

FIG. 1 is an upper right, perspective view of the precision hoe opener showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showing of the wheel, blade, and mounting bracket is included for the purpose of illustrating portions of the precision hoe opener and forms no part of the claimed design.
